(57) **CLAIM**

The ornamental design for a multi-port protection device, as shown and described.

DESCRIPTION

FIG. 1 is a front perspective view of a multi-port protection device showing my new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof; and,

FIG. 7 is a bottom perspective view thereof.

The broken lines shown depict the portions of the multi-port protection device that form no part of the claimed design. The multi-port protection device is shown with a symbolic break in its length. The appearance of any portion of the article between the break lines forms no part of the claimed design.
